FOOT CONTROLLED WASH FOUNTAIN

Howard G. Mullett and Edward D. Wachter, Jr.,
Whitefish Bay, Wis., assignors to Bradley Wash-
fountain Co., Milwaukee, Wis., a corporation of
Wisconsin

Application January 15, 1944, Serial No. 518,373

3 Claims. (Cl. 74—512)

The invention relates to wash fountains and more particularly to those in which the water to the spray head for the fountain is controlled by a foot-operated valve.

The general object of the invention is to provide a foot-controlled valve mechanism of simple construction and one which may be readily used for fountains having the water supply coming in either from below or above the basin and either for full circular or semi-circular type fountains. The invention further includes an improved arrangement for operating valves of the type shown in the prior U. S. Patent No. 2,243,957, of June 3, 1941, to H. E. Heine and Howard G. Mullett.

The invention further consists in the several features hereinafter set forth and more particularly defined by claims at the conclusion hereof.

In the drawings:

Fig. 1 is a vertical sectional view taken on the line 1—1 of Fig. 2;

Fig. 2 is a plan view of a wash fountain having the foot-control valve mechanism embodying the invention, parts being broken away;

Fig. 3 is an enlarged detailed sectional view taken on the line 3—3 of Fig. 2;

Fig. 4 is a detailed vertical sectional view taken on the line 4—4 of Fig. 5;

Fig. 5 is a detailed horizontal sectional view taken on the line 5—5 of Fig. 4;

Fig. 6 is a detailed vertical sectional view through the foot-controlled valve;

Fig. 7 is a view partly in section of a wash fountain having an overhead water supply and equipped with a foot-controlled valve mechanism embodying the invention;

Fig. 8 is a vertical sectional view through the drain connections for the fountain taken on the line 8—8 of Fig. 7;

Fig. 9 is a detailed horizontal sectional view taken on the line 9—9 of Fig. 7;

Fig. 10 is a detailed sectional view taken on the line 10—10 of Fig. 9;

Fig. 11 is a vertical sectional view similar to Fig. 1 showing certain modifications and taken on the line 11—11 of Fig. 12;

Fig. 12 is a plan view of the modification shown in Fig. 11, parts being broken away.

Referring to the drawings, the numeral 15 designates a pedestal and 16 a wash basin mounted thereon, both of these parts being formed of a suitable cement and stone composition, the pedestal having suitable handholes 17 formed therein and the basin having a centrally disposed hole 18 and an offset drain opening 19.

A spray head 20 provided with a series of spray

openings 21 to direct the water outwardly and downwardly toward the side of the basin is supported above the basin on a hollow tubular support 23 mounted at its lower end in a counterbore 13' of the hole 18, these parts being secured in assembled position by a threaded tension rod 24 connected at its upper end by a nut 25 with a cap 26 engaging the spray head and at its lower end operatively connected by a nut 27 with a transversely disposed bar 28 which spans the hole 18.

The opening 19 has a suitable drain fitting 29 mounted therein connected with a drain pipe 30.

The spray head 20 is supplied with water 15 through a supply pipe 31 connected to a shut off valve structure 32 which receives its water from a volume control valve structure 33 which in turn receives a supply of tempered water from a mixture control valve 34 which proportions the 20 water entering from a hot water pipe 35 and a cold water pipe 36. The mixture control valve and the volume control valve have not been shown in detail but may be of any suitable or well known construction, and these valves have 25 the operator controlled handles 37 and 38 connected to them, so that by turning the handle 37 the position of the volume control valve relative to its seat may be regulated to control the amount of tempered water delivered to the pipe 20 31, and by turning the handle 38 the position of the mixture valve may be regulated to control the relative amount of hot and cold water forming the tempered water supply for the pipe 31.

The shut off valve is one of the flush valve type 35 with an adjustable closing period, the one shown in Fig. 6, as far as the valve details are concerned, being substantially the same as that shown in the prior U. S. Patent No. 2,243,957, to H. E. Heine and H. G. Mullett, of June 3, 1941, but the present 40 design embodies an actuator for the valve operating member which can be operated in different angular positions. More particularly, the operating button 34 of the patent has been replaced by a short piston 39 and a headed shaft 40. The piston 39 is slidably mounted in the guide bore 41 of a ring 42 which is seated in a recess 43 in a cap 44 which has a flanged end 45 against which the disk head 47 of the shaft 40 abuts, said cap having a tapered opening 48 in said flanged end. 45 With this construction pulling or pushing on the outer end of the shaft 40 causes its disk head 47 to act as a lever engaging at one point of the end 45 and swinging about this point and thus exerting an inward thrust on the piston 39 causing it 50 to flex the diaphragm and to open the pilot valve 55

26' against the action of the spring 25' and thus permitting the pressure of the water in the inlet 5' acting on the valve 23' to open the same and allow water to pass to the outlet 6', all as more particularly described in the aforementioned patent.

In the type of installation shown in Fig. 1 the water supply comes in from below while in the form shown in Figs. 7 to 10 the water supply comes from above the basin. In this form the pedestal, basin, spray head, the tubular support, the mixing valve, volume control valve, and shut off valve are the same as in the first described construction and have been similarly designated. The valves 34, 33, and 32 are, however, above the basin and connect with the supply pipe 31' which connects with the spray head 20 at 49, the other opening in said spray head being closed by a pipe plug 50. Also the drain opening 19 in the base has the drain 29 connected with a trap fitting 51 that connects with the drain pipe 52. The trap fitting 51 has an upwardly projecting vent pipe 53 connected to it at an intermediate point, and this vent pipe carries a clamping collar 54 provided with set screws 55 which bears upon the top of the spray head and holds said spray head and the support 23 in position relative to each other and to the basin.

In Figs. 11 and 12 a semi-circular type of wash-fountain is shown in which both the pedestal 56 and the basin 57 are designed to have a wall portion 58 that abuts the wall of a building, and the spray head 20 is mounted on this basin in the same way as in the first described construction by the hollow support 23, rod 24, nut 25, cap 26, nut 27, and bar 28, the opening 59 in the basin in which the support 23 is mounted being centrally located relative to the peripheral portion of the basin. As in the first described construction the spray head 20 is supplied with water by the pipe 31 which is supplied through the valves 32, 33, and 34 from the hot and cold water pipes 35 and 36, the valves 33 and 34 having the controls 37 and 38. The drain passage from the basin is here shown connected with a trap 60 connecting with the waste pipe 61.

In all three types of installation the foot controlled mechanism for operating the valve 32 is generally similar. In each instance a center pin 62 is mounted on or formed integral with an anchor plate 63 that is secured to the floor or foundation by screws 64 or other suitable anchor bolts.

In the forms shown in Figs. 1 to 10 the foot control mechanism including a treadle rail 65 formed of wood, metal, or other suitable material and here shown as made of wood, is carried at the outer ends of a series of radially disposed levers 66, the preferred form of joint being shown in Fig. 3 as including a screw 67, a metal washer 68, and a pair of rubber blocks or sleeves 69 by which depression of the ring 65 will move the outer ends of the levers 66 downwardly at the same time allowing a limited amount of relative movement between the ring and levers to compensate for the arcuate path of movement of the lever. Also the lever 66 may be forked to engage the foot rail as shown in Fig. 1 of U. S. Patent No. 1,574,700, to L. Schlesinger et al., of February 23, 1926, and this latter construction is preferred where the foot rail is a rubber covered metal rail.

Each lever 66 is formed from a single piece of wood, metal, or other suitable material, and here shown as made of wood, having a fulcrum boss 70 and a forked inner end 71 to engage a pin 72

75 removably mounted in the sides 73 of one of the sockets 74 formed in the lever guide 75 which is vertically slidably mounted on the center post 62 and is normally held in its lowered or "valve open" position by a spring 76 interposed between said guide and a cap 77 held in position by a cotter pin 78 mounted in said post. Each lever 66 projects through a slot or hole 79 formed in the base of the pedestal 15, and its fulcrum is held against the lower side of said slot by a compression spring 80. It will be understood that the fulcrum boss of the lever may engage with any suitable flat surface, for example, the floor or foundation on which the pedestal is mounted if found more convenient for installation purposes. Accidental release of the forked end of each lever 66 from its pin 72 is prevented by a pin 81 vertically mounted in the forked portions of said lever.

10 The lever guide 75 has a boss 82 formed at one corner having a vertically disposed hole 83 therein in which a rod 84 is loosely mounted, said rod having a bent end 85 engaging said boss and threaded at its upper end 86 to receive nuts 87 and 88. The threaded end 86 extends loosely 15 through a slot 89 in one end of a lever 90 which is pivotally mounted intermediate its ends on a pin 91 carried by the forked upper end 92 of the post 62. A spring 93 surrounding the rod and interposed between said lever guide and said lever 90 holds these parts in assembled relation and acts to transmit the lifting force of the guide 75 to the lever 90.

20 The other end of the lever 90 has a hole 94 therein to receive the bent or hooked end of a link 30 rod 95 connecting said lever to the shaft 40 of the shut off valve 32, the connection with said shaft being effected by passing the end of the rod loosely through a slot or hole in the shaft and placing a rounded end stop sleeve 96 on said rod 25 through a slot 97 in the shaft 40 and be secured in position by a set screw 98.

25 In the form shown in Figs. 1 and 2 the link rod 95 is relatively short and operates entirely 35 within the hollow of the pedestal while in Figs. 7 to 10 the rod 95 extends upwardly through the hollow support 23 and the opening 99 in the spray head 20 and through a passage 100 in the collar 54.

40 The foot control mechanism shown in Figs. 11 and 12 is identical with that shown in Fig. 1 except that the half ring rail 65' is pivotally mounted at its ends 101 on studs 102 mounted in the pedestal 56 and only one lever 66 is used to operate the guide 75. All similar parts have been 45 similarly referenced.

50 With these constructions when the operator presses down on the rails 65 or 65' at any point along their length, lever or levers 66 will be swung downwardly at their outer end or ends, and their inner end or ends will swing upwardly causing an upward movement of the guide 75 on the post 62 against the action of the spring 76 and through the spring 93 causing a swinging movement of the lever 90 so as to pull down on the link rod 95 in either of the forms and thus cause the shaft 40 to be canted downwardly at its outer end and its disk 47 to fulcrum at one point on the flange 45 to push the piston 36 inwardly to operate the 55 pilot valve 26' and as a consequence the shut off valve 23' which remains open so long as the foot rail or treadle is down. When the operator takes his foot off the treadle 65 or 65', the spring 76 returns the foot operated mechanism to its initial position, and the spring 25' returns the valve 60

parts to their closed position. During the return of these parts to initial position the rod 84 may act as a tie between the guide 75 and the lever 90 so as to bring the lever 90 to its initial position. The spring 95 permits a certain amount of overtravel of the guide 75 relative to the lever 90.

We desire it to be understood that this invention is not to be limited to any particular form or arrangement of parts except in so far as such limitations are included in the claims.

What we claim as our invention is:

1. In a treadle mechanism, the combination of a shaft having a disk-shaped head, an operating piston engaged by said head, a casing for said piston engaged by said head and forming a fulcrum support, a foot treadle, a post, a lever guide slidably mounted on said post, a lever operatively connecting said treadle with said guide, a lever pivotally mounted intermediate its ends on said post, a link operatively connecting said shaft with 20 said last named lever, and a yielding drive connection between the other end of said lever and said lever guide.

2. In a treadle mechanism, the combination of a foot rail, a plurality of levers operatively connected at their outer ends to said foot rail, pivotally supported intermediate their ends and having forked inner ends, a guide member connecting all of said levers together for simultaneous movement having a socket portion for each lever, 25 30

transverse pins mounted on the walls of said socket portions and engaging the forked ends of said levers, a fixed post on which said guide member is slidably mounted, a lever pivotally mounted on said post, an oscillatory member, a link operatively connecting said oscillatory member with one end of said last named lever, and a yielding drive connection between the other end of said lever and said guide member.

3. In a treadle mechanism, the combination of an oscillatory member, a foot rail, a plurality of levers operatively connected at their outer ends to said foot rail, pivotally supported intermediate their ends and having forked inner ends, a guide member connecting all of said levers together for simultaneous movement having a socket portion for each lever and an offset boss, transverse pins mounted on the walls of said socket portions and engaging the forked ends of said levers, a fixed post on which said guide member is slidably mounted, a lever pivotally mounted on said post, a link operatively connecting said oscillatory member with one end of said last named lever, a rod extending between said boss and the other end of said lever, and a spring mounted on said rod and engaging said boss and said lever to transmit an opening motion to said last named lever.

HOWARD G. MULLETT.
